UNITED STATES PATENT OFFICE

142,907

DESIGN FOR A DOLL

Lillian R. Reinert, Hammond, Ind.

Application June 20, 1945, Serial No. 120,211

Term of patent 7 years

(Cl. D34—4)

To all whom it may concern:

Be it known that I, Lillian R. Reinert, a citizen of the United States, residing at Hammond, in the county of Lake and State of Indiana, have invented a new, original, and ornamental Design for a Doll, of which the following is a specification, reference being had to the accompanying drawing, forming part thereof.

I claim:

The ornamental design for a doll, as shown.

LILLIAN R. REINERT.
